TESTING ELECTRODE

Carl J. Schmid, New York, N. Y., and William J. Koch, Midland Park, N. J., assignors to Julius Schmid, Inc., New York, N. Y., a corporation of New York

Application March 13, 1945, Serial No. 582,528

6 Claims. (Cl. 175—183)

1

The present invention relates to testing apparatus, and more particularly to an improved mandrel for testing thin tubular rubber articles which are open at one end and closed at the other.

Heretofore it has been customary to test prophylactic rubber articles of tubular shape for defects by placing the same on a mandrel of substantially cylindrical shape and substantially conforming to the shape and size of the articles, and then subjecting the articles to test media. A serious difficulty encountered in connection with the foregoing procedure is that in placing the article on a mandrel a quantity of air is entrapped between the surface of the mandrel and the article forming air pockets between the mandrel and the article which interfere with the testing of the article. A common annoyance is that under the foregoing conditions it is impossible to make a proper test of the entire article by automatic electrical test means because of the presence of the air between the article and the mandrel.

An object of the present invention is to eliminate the foregoing difficulties and objections.

Another object is to provide simple and inexpensive means for accomplishing the foregoing.

Another object is to provide an improved mandrel having surface formations for venting, evacuation or permitting the escape of air entrapped between the mandrel and the article.

A further object resides in the arrangement of the means for accomplishing the foregoing.

Other and further objects of the present invention will be manifest from the following description and the accompanying drawing.

In accordance with the invention, the foregoing objects and advantages may be accomplished by providing a mandrel having ribs or grooves on the surface thereof distributed throughout the area of the surface to provide fluid flow passages for permitting the escape of entrapped air. These passages need not be of any particular design or pattern so long as they are effective to conduct the entrapped air to the open end of the article.

Embodiments of the invention as shown in the accompanying drawing are for purposes of illustration and are not intended as limitations.

In the drawing:

Fig. 1 is an elevational view of a mandrel, with an article thereon, illustrating one embodiment of the invention;

Fig. 2 is a sectional view taken along the line 2—2 of Fig. 1;

2

Fig. 3 is an elevational view of a mandrel with an article thereon illustrating another embodiment of the invention;

Fig. 4 is a bottom plan view of the mandrel of Fig. 3;

Fig. 5 is an elevational view of a mandrel illustrating another embodiment of the invention; and

Fig. 6 is an elevational view of a mandrel illustrating still another embodiment of the invention.

Referring to the drawing in detail wherein like parts are indicated by the same reference characters, there is shown a mandrel 10 of the type 15 for testing thin tubular or hollow rubber articles 12 shown in section in Figs. 1 and 3 and being open at one end and closed at the other end, such as, for example, prophylactic rubber articles. Such a mandrel has one end attached to a support 20 constituting a part of a testing machine as shown in Fig. 1 of U. S. Patent 2,297,837, and has a free end 14 which is substantially hemi-spherical in shape. The body of the mandrel is substantially cylindrical and conforms substantially to 25 the natural or normal shape of the article 12 so that the article lies in close contact with the mandrel without undue stretching of the article to thereby provide the desired conditions for testing the article.

In Figs. 1 and 2, the means for attaining the 30 benefits of the present invention are illustrated as of longitudinally extending and circumferentially spaced grooves or recesses 16, preferably of capillary or minute dimensions, herein shown as eight in number, although any suitable number may be provided. These grooves extend from the apex of the hemi-spherical end 14 upwardly 35 along the side walls of the mandrel to a point above the upper end of the article placed on the mandrel.

In this manner, any air entrapped between the mandrel and the article can escape or is vented or evacuated by way of the grooves 16 to the atmosphere, thereby eliminating air pockets causing 40 improper test conditions.

In Figs. 3 and 4 the foregoing results are attained by providing a plurality of ribs or ridges 45 18 similarly arranged as the grooves to provide a space between the article and the mandrel adjacent these ribs or ridges for permitting the escape of entrapped air.

In Fig. 5, longitudinal grooves 16 are illustrated, each provided with a series of fluid flow connected tributaries or transverse passages 20 herein 50 shown arranged in "herringbone" manner with

the outward end of the passages of one groove 16 in fluid flow communication with passages of an adjacent groove 16, whereby the means for permitting the escape or evacuation of entrapped air are distributed over substantially the entire 5 surface of the mandrel.

In Fig. 6, means for facilitating the escape of entrapped air are shown in the form of a crazed design or short grooves or recesses 24 radiating from a common center 26 and having their outward ends in fluid flow communication with the outward ends of grooves 24 of other groups. The grooves may be arranged in a regular or symmetrical pattern, such as five or six grooves 24 in a group or may be arranged in an irregular pattern, if desired as will be readily appreciated. By utilizing this embodiment of the invention substantially the entire surface of the mandrel is provided with means for preventing the formation of air pockets.

In carrying out the electrical testing of the article, in the manner, for example, as disclosed in the aforementioned patent, the mandrel constitutes one terminal of an electrical circuit and the liquid or other medium contacting the outer surface of the article constitutes the other terminal so that in the event of a defect in the article current will pass through the article to complete the electric circuit to a signal or other device.

It is to be understood that the grooves, recesses, ribs, ridges, etc., which form the means for evacuating air from between the article and the mandrel as shown in each of the figures of the drawing are greatly enlarged. In actual practice these passages are made very minute so as not to interfere with the electrical test.

From the foregoing description it will be seen that the present invention provides an improved mandrel for testing rubber articles of the class described. The entrapped air-removing means may take many different shapes and forms and are adapted to be readily formed on the surface of the mandrel in any suitable manner.

It is to be understood that while we have illustrated and described three forms or embodiments of our invention we do not wish to be limited to those precise forms as various changes and modifications may be made therein without departing from the spirit and scope of our invention.

What we claim is:

1. A mandrel for testing thin tubular rubber articles open at one end and closed at the other and adapted to snugly fit the mandrel without the entrapment of air between the mandrel and the article, said mandrel comprising an elongated cylindrical body of electrical conductive material having a series of passages in the surface thereof effectively connected for fluid flow communication and distributed over substantially the entire outer surface of said mandrel for permitting the escape or evacuation of air from between the mandrel and the article as the article is applied to the mandrel.

2. An article of manufacture comprising a mandrel for testing thin tubular rubber articles open at one end and closed at the other and adapted to snugly fit the mandrel without the entrapment of air between the mandrel and the article, said mandrel comprising an elongated cylindrical body of electrical conductive material having one end adapted for mounting and its other end free, said body being of a length greater than the length of the article to be tested where-

by the open end of the article will terminate short of said first mentioned end of the mandrel, said body having formations in the surface thereof providing passageways along the outer surface extending from predetermined points on the surface of the body to adjacent said first mentioned end thereof whereby to permit the escape or evacuation of air from between the body and the article to the atmosphere as the article is applied to the mandrel.

3. An article of manufacture comprising a mandrel for testing thin tubular rubber articles open at one end and closed at the other and adapted to snugly fit the mandrel without the entrapment of air between the mandrel and the article, said mandrel comprising an elongated cylindrical body of electrical conductive material having one end adapted for mounting and its other end free, said body being of a length greater than the length of the article to be tested whereby the open end of the article will terminate short of said first mentioned end of the mandrel, said body having surface indentations therein in communication with each other along the outer surfaces thereby providing fluid flow passages extending from predetermined points on the surface of the body to adjacent said first mentioned end thereof whereby to permit the escape or evacuation of air from between the body and the article to the atmosphere as the article is applied to the mandrel.

4. An article of manufacture comprising a mandrel for testing thin tubular rubber articles open at one end and closed at the other and adapted to snugly fit the mandrel without the entrapment of air between the mandrel and the article, said mandrel comprising an elongated cylindrical body of electrical conductive material having one end adapted for mounting and its other end free, said body being of a length greater than the length of the article to be tested whereby the open end of the article will terminate short of said first mentioned end of the mandrel, said body having a groove formation in the surface thereof providing passageways extending from predetermined points on the surface of the body to adjacent said first mentioned end thereof whereby to permit the escape or evacuation of air from between the body and the article to the atmosphere as the article is applied to the mandrel.

5. In testing apparatus, an elongated substantially cylindrical mandrel body of electrical conductive material constituting one terminal of an electrical testing circuit, said body being adapted to support a thin hollow member of dielectric material to be tested and to be immersed in a liquid constituting the other terminal of said circuit, said body having surface formations thereon providing communicating passageways extending from predetermined points on the surface of the body along the outer surface to adjacent one end thereof whereby to permit the escape or evacuation of air from between the mandrel and the article to the atmosphere when the article is applied to the body.

6. In a testing device, an elongated substantially cylindrical body of electrical conductive material constituting one terminal of an electrical testing circuit, one end of said body being adapted for mounting with its other end free, and being adapted to support a thin hollow member to be tested having a closed end and an open end and being of dielectric material, the body with the member thereon being adapted to be immersed

in a liquid constituting the other terminal of said circuit, said body having minute formations in the surface thereof providing communicating passageways extending from predetermined points on the surface of the body along said surface to adjacent said end thereof, whereby to permit the escape or evacuation of air between the mandrel and the article from said predetermined points to the atmosphere at said end of the body when the article is applied to the body.
